CLAIM

The ornamental design for a bottle, as shown and described.

DESCRIPTION

FIG. 1 is a right side elevation of a bottle showing my new design, the left side elevation being a mirror image of that shown;

FIG. 2 is a front elevational view thereof;

FIG. 3 is a rear elevational view thereof;

FIG. 4 is a top plan view thereof;

FIG. 5 is a bottom plan view thereof; and

FIG. 6 is a sectional view taken along the line 6—6 in FIG. 2.

FIG.1

FIG.2

FIG.3

FIG.4
